O. LUSCHER

CLOTH TRIMMING DEVICE

Filed June 16, 1922

Inventor

Oscar Luscher

By William C. Linton.

Attorney

UNITED STATES PATENT OFFICE.

OSCAR LUSCHER, OF NEW LONDON, CONNECTICUT.

CLOTH-TRIMMING DEVICE.

Application filed June 16, 1922. Serial No. 592,844.

To all whom it may concern:

Be it known that I, OSCAR LUSCHER, a citizen of the United States of America, residing at New London, in the county of New London and State of Connecticut, have invented certain new and useful Improvements in Cloth-Trimming Devices; and I do hereby declare that the following is a full, clear, concise, and exact description of the invention, such as will enable others skilled in the art to which it appertains to make and use the same.

This invention relates to improvements in cloth trimming devices for use upon sewing machines, having for an object to provide a novel form of cloth trimming device and holder for the knife or cutting blade thereof capable of being adjusted both horizontally and vertically whereby the knife may be properly positioned to cut or trim the cloth before the stitching of the same.

Another and equally important object of the invention is to provide the blade holder for the device which may be formed in a single casting or similar operation, having a portion of the same shaped to present a slideable hanger arm whereby horizontal adjustment of the knife may be effected, while another portion thereof is provided with means for adjusting the knife.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a side elevation of the improved trimming device:

Figure 2 is a similar view taken at substantially right angles to the Figure 1; and,

Figure 3 is a detail in perspective of the improved knife holder.

Having more particular reference to the drawings, in connection with which like characters of reference will designate corresponding parts throughout, A represents a fragment of the usual head of a sewing machine arm, the same being provided with a depending hanger 1, having a presser foot 2 adjustably connected thereto as at 3, while the reciprocal needle bar 4 is also received in said head A and is adapted to carry

on its lower end a suitable needle 5. A reciprocal trimmer bar 6 is likewise movably mounted in the head A and has a right angularly disposed shoulder 6' formed on its lower end, the purpose of which will be hereinafter described.

The invention may be stated to comprise a holder generally indicated by the numeral 7, comprising a body portion having a right angularly disposed longitudinally slotted hanger arm 8 formed integral with one end thereof, said hanger arm being substantially right angular in cross section in shape and having an under cut portion 9 therein. One side of the forward end portion of the body 7 is provided with a vertically disposed seat 10 which in turn is adapted to receive the upper or shank portion of a knife or cutting blade 11 therein, said cutting blade having its shank portion bifurcated, as at 12 and adapted to receive securing screws 13 therein, these screws, in turn, being engaged in suitably arranged screw threaded openings formed in the inner side of the seat 10. Thus, it will be understood that means are provided for securing the knife blade 11 in a vertically adjusted position with respect to the body portion of the holder 7.

The right angularly shaped hanger arm 8 of the holder is adapted to be engaged with the lower end of the reciprocal trimmer bar 6, the under cut portion 9 thereof receiving the right angularly disposed shoulder 6' formed on said lower end of the trimmer bar 6, whereupon a securing screw 14 is passed through the longitudinally disposed slot in said hanger indicated for the purpose of convenience by the numeral 15, into engagement with a screw threaded opening formed in the lower portion of the trimmer bar 6. Obviously, by tightening the screw 14, the hanger arm together with the body portion of the knife holder will be secured in a horizontally adjusted position.

It is to be noted that the arrangement of the cutting blade or knife 11 is such as to cause disposition of the same forwardly of the needle 5 and in proximity to the forward or free extremity of the pressure foot 2. Hence, said trimmer knife will function during operation of a machine to trim or cut fabric prior to the stitching of the same by the needle 5. Because of the juxtapositioning of the cutting edge of the knife 11 with relation to the forward or free extremity of the pressure foot 2, it will be likewise under-

stood that the cloth will be firmly secured with relation to the work board of the machine during a cutting operation and in this way, an even trim or cut of the fabric will be ensured.

By adjusting the hanger arm 8 along the lower end of the reciprocal trimmer bar 6, the lateral positioning of the blade 11 with respect to the needle 5 may be varied, such as conditions or preference may dictate. Furthermore, to effect vertical adjustment of the knife 11, the screws 13 may be loosened and the knife moved either upwardly or downwardly, whereupon said screws may be retightened upon the bifurcated portion 12 of the cutting blade or knife 11.

During operation of the trimmer, it of course will be understood that the reciprocal trimmer bar 6 will be reciprocated at the rate of speed sufficient to cause the bevelled cutting edge of the trimmer knife 11 to be engaged with the fabric in a manner to quickly and evenly sever or trim the same. The extent of engagement of the bevelled cutting edge of the knife may as hereinbefore stated, be varied by vertical adjustment

of such knife through the medium of the securing screws 13.

Manifestly, the construction shown is capable of considerable modification, and such modification as is within the scope of my claim, I consider within the spirit of my invention.

I claim:

A trimmer blade holder comprising a substantially right angular body portion, said body portion having a vertical recess formed in one of the side walls thereof adjacent its forward end for adjustably receiving a trimmer blade, a right angularly disposed hanger arm being right angular in cross section, the lower wall of said hanger arm being formed integral with the upper face adjacent the rear end of said body portion, one face of the vertical wall of said hanger arm having a longitudinally extending recess therein, and the vertical wall of said hanger arm having a longitudinally extending slot therein.

In witness whereof I have hereunto set my hand.

OSCAR LUSCHER
